ABSTRACT OF THE DISCLOSURE

The survival snowshoes of this invention comprise a detachable portion of an exterior garment, preferably the sleeve lining, provided with slittable areas or attached tab loops. If the driver of a snow vehicle is stranded, he may detach the lining, thrust sticks through the slits, loops, or other means provided, and by lacing the stick-supported lining to his boot make an emergency snowshoe.

This invention relates to survival snowshoes.

The advent of small over-the-snow vehicles has produced a new hazard that, should the vehicle fail, the driver of the vehicle may be stranded in deep snow miles away from persons who know of his predicament. Unless he carries snowshoes which will allow him to walk out from the area in which he was stranded, he is in serious danger—so much so that some park and forest land supervisors will not allow a snow vehicle to be operated in their areas unless the driver carries an effective walkie-talkie. But this is by no means a universal practice, and many times a driver of a stranded vehicle must rely on his own resources.

The present invention provides a means by which a stranded driver may walk out, even though he carries no snowshoes.

Recently special down-filled or insulated snowmobile suits have appeared which protect the driver from the weather much better than formerly. In carrying out my invention, I provide such suits, or in fact any coat or article of exterior clothing, with special detachable linings. The linings are sewn into the coat by a chain stitch, or are attached to the garment by slide fasteners, or in any other quickly detachable manner. When the wearer becomes stranded, he pulls these linings away from the garment and converts them into emergency snowshoes in a manner which will appear from the specification and the drawings, in which

FIG. 1 is a plan view of the lining after its removal from the sleeve of the garment,

FIG. 2 is a plan view of the same lining after it has been stiffened and reinforced by sticks,

FIG. 3 is a detailed view showing the lining finished with tab loops,

FIG. 4 is an enlarged detail showing the fused pattern in the thermoplastic lining used to form the lacing eyelets, and

FIG. 5 shows a portion of a sleeve lining transversely stitched to form a series of tubes in which reinforcing sticks may be placed.

Although the lining, or in fact any portion of a garment, may be used to form the supporting surface of an emergency snowshoe, sleeve linings have the approximate size and shape to make them particularly suitable. Accordingly, the preferred example shows a sleeve lining adapted for use as an emergency snowshoe. Other portions of a garment may be treated in the manner which this specification sets forth.

The fabric of which the lining is made can be formed of any strong textile material, and conveniently can be formed of thermoplastic fibers such as nylon, polyethylene terephthalate, or one of the polyester thermoplastic textile fibers.

2

To obviate confusion, the surface of the lining which is hidden while in the garment will be called the "lower surface." That face of the lining which is exposed when the lining is in normal position in the garment will be called the "upper surface."

As FIG. 1 shows, the spread-out lining 10, removed from the sleeve of a garment bears a number of parallel fused lines 11—11, in which the textile nature of the fabric is lost. These fused lines are distributed over the surface of the lining 10, in such a way that by slitting the thermoplastic in the fused area and pushing the intermediate fabric either up or down, loops 12—12 will be formed which may hold reinforcing sticks which give rigidity to the snowshoe. The sticks are saplings of approximately $\frac{3}{4}$ of an inch in diameter, and are broken off by the operator from growth at the location of the stranded machine. As a specific example, a snowshoe which will support a man weighing at least 175 lbs. requires a rear stick 13, approximately 25 inches long, an intermediate stick 14, approximately 20 inches long, and a forward stick 15, which is 15 inches long.

Stick 15 is the so-called "roll stick," and is threaded through the fabric loops in such a manner that it lies on the upper surface of the fabric. Its position allows the boot to tip up and down while walking. The toe hole in the filling of a conventional snowshoe is not necessary since the cloth will bend downwards beneath the pressure of the toe of the wearer's boot.

Two sticks 16 and 17 are threaded through the loops in the fabric to form a cross, with the rear end of stick 16, e.g. terminating on the lefthand side of the fabric at the rear of the snowshoe, and stick 17, terminating on the right.

Lacings 18, which pass over the instep and also around the heel of the shoe are threaded through small eyelets 19, which are made by fusing the fabric 10, in the manner shown in detail in FIG. 4. The fused area 21 may be pushed or cut out of the cloth. Lacings 18, in the made-up garment are attached to the lining and, when the lining is in place in the garment, lie between the lining and the outer sleeve, and so cannot be lost or misplaced prior to the emergency.

As FIG. 3 shows, instead of slits being made in the lining, tape loops 22 and 23 may be attached to the lower surface of the lining, the exception being loops which hold the roll stick. These must appear on the upper surface of the snowshoe. Full directions for use may be printed on the lining itself or on the label 24, which is attached to the garment.

An alternate construction is shown in FIG. 5 where, instead of forming loops in the lining to hold the sticks, the lining is two-ply and is stitched, or otherwise fastened in any appropriate manner along lines running transversely across the lining. In effect, a series of tubes is made through which the sticks may be thrust. Two sticks 25 and 26 are laid on the upper surface parallel to its longitudinal center line and are held in position by lacings 18a, which pass through eyelets formed in the same manner as the eyelets 19.

Transverse corrugations occur on the snow-contacting surface of the snowshoe shown in FIG. 5. They are of considerable advantage in descending steep slopes, and grip if the snow is a little crusty.

The same advantages can be attained in the snowshoe of FIG. 2. The sticks can be so placed in the loops as to appear on the snow-contacting surface, and are very effective in preventing slippage on crusted snow or on steep grades.

The expedient of forming a lining or any portion of a garment in such a manner that it can be used as an emergency substitute for a standard snowshoe adds very little to the cost of a garment. Because it is highly unlikely that

anyone will travel on a snow vehicle without suitable outside clothing, if the clothing possesses the detachable elements of this invention, it is impossible for anyone to be stranded without having the means to walk away from the stranded vehicle. The coat will not be forgotten as loose snowshoes could be, and should a person be stranded and have the means to walk out on deep snow, there is little chance that he will become lost. Snow vehicles make a substantial track. The stranded driver has only to follow this track to come out at the place from which he started.

I claim:

1. A garment having an outer ply and a lining, a portion of which lining is adapted to be detached from said garment to form the supporting surface of an emergency snowshoe, having means incorporated in the said portion to retain sticks to afford both transverse and lateral rigidity to said portion, and lacings affixed to said portion and normally lying between the inner and outer plies whereby a foot may be laced to the extended supporting surface.

2. A garment provided with a detachable portion adapted to form the supporting surface of an emergency snowshoe wherein the said detachable portion is formed of thermoplastic fibers, and wherein at specified intervals distributed over the face of said portion, the said thermoplastic fibers are fused together, thereby producing an area which may be cut or split to create loops extending above and below the extended surface of said portion, adapted to receive transverse and longitudinal supporting sticks when the detached portion is to be used as the supporting surface in an emergency snowshoe.

5 3. A garment having a portion of said garment which may be detached to form the supporting surface of an emergency snowshoe, the said detachable portion being formed of two plies of lining material stitched together by a plurality of transverse stitchings extending from one lateral margin to the other and forming a tube wherein sticks can be thrust into the space between the plies to maintain the said portion in a laterally extended condition, the said fabric having eyelets to provide for the attachment of longitudinal sticks thereby providing for longitudinal stiffness in the said emergency snowshoe.

10 15 4. A garment as claimed in claim 1 wherein the detachable portion bears on its exposed surface printed directions for the conversion of the detachable portion to an emergency snowshoe.

15 20 5. A garment as claimed in claim 1 wherein the detachable portion of said lining bears a multiplicity of loops arranged to receive and hold reinforcing sticks to give transverse and longitudinal rigidity to the said portion when it is to be used as a supporting surface of an emergency snowshoe.
